SEWAGE SCREENING APPARATUS

Anthony J. Fischer, Manhasset, N. Y., assignor to
 The Dorr Company (Inc.), New York, N. Y., a
 corporation of Delaware

Application November 22, 1944, Serial No. 564,690

15 Claims. (Cl. 210—44)

1

This invention relates to the treatment of raw sewage, and more particularly to the screening stage which may precede the removal of solids from the sewage by settling.

The screening stage as herein contemplated employs a bar screen for intercepting sewage solids of a size which it is not desirable to have pass on into a subsequent treatment stage such as settling, and it further contemplates the use of a screen in conjunction with comminuting apparatus whereby the screenings or screen rejects are reduced prior to being re-introduced into the stream of sewage for further treatment. The screenings collection or at the screen and are currently or periodically removed therefrom for comminution.

It is among the objects of this invention to produce an improved combination screening and comminuting apparatus which is simple, relatively inexpensive, easy to operate and overhaul, and which is compact, requiring a minimum of concrete work, gates, valves, penstocks or the like.

The basic form of the apparatus according to this invention is simplified for instance, in that it avoids the by-pass channel and accessories thereof as found in some known apparatus combination of this class, also in that it dispenses with special mechanical automatic screen cleaning means found in another class, whereby sewage solids retained on top of a bar screen are raked to the comminuting apparatus.

Another object is to provide for a combination screening and comminuting apparatus which allows to convert from one mode of operation to another, namely from the mode of automatic self-cleaning operation of the screen while the comminuting apparatus is available for this operation, to a mode of cleaning the screen by removing sewage solids therefrom to a point outside the sewage stream when the comminuting means are not available for automatic self-cleaning.

I attain these objects by providing a construction in which I intercept the sewage solids at the underside of a substantially horizontal screen, in which I draw the solids together with liquid from underneath, that is from the influent side of the screen, deliver them to comminuting treatment and then return them to the sewage stream. My construction further provides means to optionally move the screen from its normally horizontal position to a substantially inclined solids intercepting position permitting the intercepted solids to be raked up the incline to a point of discharge or disposal above the liquid level during such periods as the comminuting apparatus is not available for normal self-cleaning operation.

2

According to one feature the bar screen is mounted so as to be positionable by a swinging movement from a normally horizontal totally submerged solids intercepting position to an abnormal inclined partially emerged solids intercepting position.

According to another feature the bar screen is swingable about trunnions from the one to the other position.

10 According to a still more specific feature the bar screen that is swingable about the trunnions has a handle member for manipulating the screen from an operating platform above the sewage screen, and also serving as a locking means for securing the bar screen in at least one of its positions.

Still further expressed the invention is embodied in combined screening and comminuting apparatus having a flow-channel structure embodying a bottom and transversely-spaced side walls rising therefrom and defining a downstream flow-channel portion wherein there is interposed a transversely-extending bar screen of which the bars are transversely-spaced. The screen is tilttable about a horizontal and transversely-extending axial line into a selected normal operative position therefor whereat it is located so as to provide a screening roof affording at the underside thereof an upstream or flow-receiving face immediately overlying a solids settling-out region within which screen-out solids of certain selected sizes are received and from which such solids can be removed by a disintegrating type of pumping means and from which solids pumped thereby are deliverable therefrom and returnable as pumped comminuting solids to the sewage flow screen. The screen is also tilttable about said axial line into a selected extreme abnormal operative position therefor by a movement in which the forward end of the screen moves downwardly into engagement with the bottom of the channel structure while the previous rear end of the screen moves upwardly into an elevation proximate that of the upper edge of the side walls, to

45 wit, into an abnormal operative position in which the flow-receiving face of the screen when in normal operative position therefor has become the flow discharge face and is located at the underside of the abnormally positioned screen. While the screen in its normal operative position therefor is relatively horizontal, nevertheless the screen overlies a settling-out region but is not limited to a position whereat it is substantially horizontal, the essential functioning being that the screen is positioned so that normally the

50

under upstream or flow-receiving face portion thereof overlies and defines a roof of a solids-settling-out region but which screen is positionable for abnormal operative position by tilting the forward end of the screen downwardly and in engagement with the bottom of the flow-channel whereby the previous upper or flow discharge face of the screen of normal operative position still continues as an upper face but becomes a flow-receiving face of the screen of abnormal operative position.

The invention possesses other objects and features of advantage, some of which with the foregoing will be set forth in the following description. In the following description and in the claims, parts will be identified by specific names for convenience, but they are intended to be as generic in their application to similar parts as the art will permit. In the accompanying drawings there has been illustrated the best embodiment of the invention known to me, but such embodiment is to be regarded as typical only of many possible embodiments, and the invention is not to be limited thereto.

The novel features considered characteristic of my invention are set forth with particularity in the appended claims. The invention itself, however, both as to its organization and its method of operation, together with additional objects and advantages thereof, will best be understood from the following description of a specific embodiment when read in connection with the accompanying drawings in which

Fig. 1 is a longitudinal section through the sewage flow channel comprising screening and comminuting apparatus in combination;

Fig. 2 is a plan view upon the sewage flow channel and apparatus shown in Fig. 1;

Fig. 3 is a cross-section along the line 3—3 in Fig. 1, or along the line 3'—3' in Fig. 2;

Fig. 4 is a cross-section along the line 4—4 in Fig. 1, or along the line 4'—4' in Fig. 2;

Fig. 5 is a cross-section along the line 5—5 in Fig. 1, or along the line 5'—5' in Fig. 2.

In the drawings a raw sewage flow channel structure 10 is shown to have associated with it or interposed in it a sump or coarse solids trap 11, an upflow section or screening chamber 12, a coarse screen or vertical coarse grating 13 between the trap 11 and the screening chamber 12, with a partially submerged wall portion 14 extending transversely of the flow channel 10 above the coarse grating 13, and an emergency overflow opening 14^a being provided in the wall 14. The coarse grating 13 lodges vertically removable in vertical groove elements 13^a and 13^b fixed to the sides of the channel structure.

A bar screen 15 mounted in the chamber 12 is pivotally movable about a horizontal axis which substantially bisects the screen, as indicated by 60 trunnions 16 or the like. At one end the screen has pivotally connected therewith a handle or swingable member 17 which can be manipulated from the operating floor or platform P constituting the top of the channel structure 10. Normally the screen 15 is in the horizontal position (shown in full lines in Fig. 1) with the handle member 17 in vertical position and just protruding above the operating platform P. In this position the screen divides the screen chamber 12 into a lower or influent portion 18 and an upper or effluent portion 19.

By pulling up on handle 17 the bar screen can be rotated into the inclined (dot and dash line) position shown in Fig. 1, and it can be locked 75

in this position by turning the handle 17 from vertical down to horizontal as indicated by arrows 17^a, and allowing it to lodge in a corresponding depression 20 provided in the operating floor P.

With respect to the screening chamber 12 the flow channel 10 may be said to comprise an influent portion 21 leading thereto and an effluent portion 22 leading therefrom. The flow channel 10 structure is further defined by parallel side walls 23 and 24 which also form the side walls for the sump 11 and the screen chamber 12, and by a bottom 25.

The sump 11 is more specifically defined by a rear wall 26, a front wall 27, and a bottom 28 upon which is shown to rest a basket 29 for receiving the coarse or heavy matter sinking into trap 11, and whereby such matter may be raised from the trap 11 and above the platform P after removing a platform grating 30 above the trap.

The screening chamber or upflow section 12 is more specifically defined by the coarse grating 13, the partially submerged wall portion 14, by a horizontal bottom portion 31, and an inclined bottom portion 32 which meets the horizontal bottom 25 of the flow channel in a corner portion 33. When in horizontal position one end of the screen 15 closes upon the lower edge of the wall portion 14, while the other end of the screen closes upon the corner portion 33 of the channel bottom. A removable floor grating 34 is shown to overlie the screen chamber 12.

Upon the operating floor P is mounted a motor driven pump 35 of the solids cutting or comminuting type and herein briefly termed a cutter pump. A drive motor 36 and the pump have a common base 37 which in turn is fastened to the operating floor P. An induction pipe 38 leads from the influent side of the screen 15 to the inlet end of the cutter pump 35, which pipe is herein shown to consist of a series of flanged sections which comprise (see Fig. 1) a horizontal straight section 39, a reducing section 40, an elbow 41, an elbow 42, and (see Fig. 5) a horizontal straight section 43, an elbow 44, a vertical straight section 45, and an elbow 46 connecting with the inlet end of the pump.

The pump 35 has a dual outlet, that is a pair of outlets or flanges for connections 47 and 48 facing in opposite directions.

The outlet 47 connects with a discharge conduit 49 leading to a point of the sewage stream well past or downstream of the screen chamber 12, and shown to comprise a short flanged pipe section, a shut-off or control valve 50 of the elbow type and a vertical terminal pipe section 52 having a splash plate 52^a. The opposite pump outlet 48 connects with a discharge conduit 53 including a shut-off or control valve 54, a horizontal section 55, a T-shaped pipe section or lateral 56 connecting downwardly with a shut-off or control valve 57 and a vertical outlet branch 58 having a splash or diffusing plate 58^a and leading to a point of the sewage flow directly above or at the effluent or downstream side of the bar screen 15, the lateral 56 connecting horizontally with a horizontal pipe section 60 which in turn connects with a shut-off or control valve 59 flanged to an elbow 61 connecting downwardly with a vertical discharge branch 62 having a splash plate 62^a. If sufficient solids have collected at the influent or upstream side, that is at the underside of the screen 15, to partially clog the same, this will manifest itself by establishing a differential d between the liquid levels at the

influent or upstream and the effluent or downstream sides of the screen.

Operation

Normally the bar screen 15 is in the horizontal position shown in Fig. 1, and the cutter pump 35 is started periodically in order to transfer suspended sewage solids from the influent side to the effluent side of the screen by way of a solids-communuting step such as is being carried out by the solids reducing or cutting effect of the pump 35.

During the periods that the cutter pump 35 is not running the raw sewage passes through the flow channel 10 in the manner indicated by the full line arrows A, namely from the influent section 21 of the flow channel 10 across the coarse solids sump 11, then somewhat downwardly through the coarse grating 13 and underneath the partially submerged wall portion 14 into the influent section 18 of the screen chamber 12, then upwardly through the bar screen 15 into the effluent section 19 of the chamber 12, whence the stream continues horizontally into and through the effluent section 22 of the flow channel 10.

As the flow of sewage through the channel 10 proceeds sewage solids accumulate at or adhere to the under side of the horizontally disposed bar screen 15 gradually clogging the same to the extent that a super-elevation or differential d of liquid levels establishes itself, namely the super-elevation of the liquid at the influent side over the level of the liquid at the effluent side of the screen 15.

Periodically, that is to say either in a predetermined time cycle or else in response to a predetermined degree of super-elevation d , the cutter pump 35 is started to draw liquid and over-sized solids from the under side of screen 15 downwardly as indicated by the dot and dash line arrows B into and through the induction conduit 38, to comminute the over-sized sewage solids passing through the cutter pump, and to discharge the raw sewage containing the comminuted solids, that is, with the latter in suspension, at a suitable or desired point into the raw sewage stream in the flow channel 10. The capacity of the pump 35 is preferably greater than the flow of sewage through the channel 10, in order to enable the pump 35 to set up or induce in or to super-impose upon the normal stream of sewage the downward flow according to the dot and dash line arrows B as opposed to the general flow direction of the sewage during the periods when the pump is not operating.

Depending upon the settings of the shut-off or control valves 50, 54, 51 or 59, the sewage containing the comminuted solids may be returned to different points of the stream in the flow channel 10. If returned by way of branch outlet 53 directly above screen 15 the comminuted matter may partly pass away with the general sewage stream into the effluent section 22 of channel 10, and partly it may follow the downward flow tendency induced in or superimposed upon the sewage stream by the action of the pump 35, and pass downwardly through the screen 15 to be once more recirculated through the pump whereby recomminution of sewage solids may be effected. If sent through the branch outlet 52 the comminuted matter will largely pass away with the general sewage stream and without being recirculated or recomminuted. If sent through branch outlet 62 all the comminuted matter is compelled to pass through the influent section 18 of the

screen chamber 12 with a relatively greater chance for the sewage solids to be recirculated through the pump 35 and thus to be recomminuted, except for that portion of the raw sewage which in cases of excess sewage flow may pass unscreened from the influent section 21 of channel 10 through the emergency opening 14a directly to the effluent side of the screen 15.

The operation of the cutter pump 35 accomplishes two things, in that it reduces the solids in the raw sewage to a desirable size adapted for subsequent sewage treatment steps, and in that it removes coggings from the screen 15.

If and when the pump 35 is being overhauled or its dual function not available for any other reasons while the sewage stream may continue piling up over-sized solids, the screen 15 can be swung into the inclined (dot and dash line) position in which case what was previously the influent side of the screen 15 proper now becomes the effluent side, while the effluent side now becomes the influent side. This inclined position of the screen 15 allows the over-sized solids accumulating thereon to be raked up the incline of the screen to a point of disposal outside of the sewage stream. In this position the operation of the screen may be continued until automatic, that is self-cleaning operation of the screen can be restored along with the restoration of the comminuting step when the pump is again available for such operation.

I claim:

1. A combination sewage screening and comminuting apparatus comprising a sewage flow-channel structure embodying a bottom and transversely-spaced side walls rising from and defining a downstream channel portion; a positionable bar screen having transversely-spaced screening bars and so located with respect to the flow channel structure as to provide normally an intercepted-solids-receiving region underneath the screen and being tiltable to an opposite extreme abnormal operative position to present that which was a previous upstream flow-receiving face as a downstream flow-discharge face; trunnion means determining the location of a horizontal transversely-extending axis which substantially bisects the screen and mounted in the side walls of said channel structure whereby said screen is functionally disposed within said channel portion and is tiltable about said axis between said two extreme operating screening positions; means for withdrawing screen-out solids from said region; means for comminuting such withdrawn solids; and means for returning such suspended comminuted solids to the sewage flow.

2. The apparatus according to claim 1, in which there is provided an operating platform carried by the side walls; and in which there is included a positioning member swingably connected with an end portion of the bar screen and provided whereby to lift that end of the bar screen from normal position into an abnormal screening position; said positioning member being located with respect to the platform and swingable into horizontal position over and into engagement with said platform whereby it becomes effective to lock the bar screen in its said abnormal screening position.

3. The apparatus according to claim 1, in which said withdrawal means including solids-comminuting pump having power drive means for the pump, intake pipe means leading from the upstream side of the screen to the pump and discharge pipe means leading from the pump to ad-

jacent the downstream side of the screen when the latter is in its normal operative position, said pump and piping having sufficient volumetric capacity to force the liquid discharge from the discharge pipe means through the screen against the flow of sewage upwardly through the screen when the latter is in its normal operative position.

4. A combination of sewage screening and comminuting apparatus according to claim 1, in which a transverse partial partition extends from side wall to side wall part way downwardly within the sewage flow channel structure but terminating above and in spaced relationship with respect to the bottom of the flow-through channel portion in which the positionable screen is located which when the positionable screen is in its normal operative position therefor it is disposed whereat one end thereof closes upon the lower portion of the partial partition while the other end thereof closes upon a portion of the bottom of the sewage flow channel structure and in which the positionable screen when in abnormal position thereof is disposed whereat the end of the screen which was previously closed upon the transverse partial partition now closes upon another portion of the bottom of the channel structure.

5. A combination sewage screening and comminuting apparatus according to claim 1, in which the sewage-flow channel structure embodies a transversely-extending wall portion constituting a partial partitioning means extending downwardly within the flow channel portion but terminating in vertically-spaced relationship with respect to the bottom of the flow-channel structure and in which the positionable bar screen is tiltably carried on and by a transversely but horizontally-extending axial providing means which in turn is supported by and from the channel structure and in which said screen when in normal operative position therefor extends horizontally and bridges the space between the side walls and between the lower portion of the partial partitioning member and a portion of the bottom of the channel structure, which said screen when tilted into its abnormal operative position moves so that the forward upstream end swings downwardly and rearwardly towards and into closure position with respect to a portion of the bottom of the channel structure while the other end of the screen swings upwardly and forwardly to an elevation proximate that of the top of the side walls of the structure.

6. A combination of sewage screening and comminuting apparatus according to claim 1, in which a transverse partial partition extends from side wall to side wall and part way downwardly within the flow channel structure whereat a lower portion of the partial partition terminates at elevation above and in spaced relationship with respect to said bottom and whereat the upper portion of the partial partition provides an overflow weir at elevation lower than that of the upper edge portions of the side walls and at elevation lower than that of the upper end of the positionable screen when in its abnormal operative position, in which the positionable screen when in its normal operative position is disposed whereat one end thereof closes upon the lower portion of the partial partition while the other end thereof closes upon a portion of the bottom of the channel structure, and in which the positionable screen when in its abnormal operative position is disposed whereat the end of the screen which was

previously closed upon the transverse partial partition now closes upon a portion of the bottom of the channel structure.

7. Apparatus according to claim 1, in which the channel structure thereof is provided with a depressed bottom portion for receiving screened-out solids settling within the region below the bar screen when in normal operative position therefor, in which there is provided across the downstream channel portion a preliminary coarse screen located upstream with respect to the positionable screen in any operative position of the latter, and in which the means for returning suspended comminuted solids includes a pump and discharge conduit section adapted for delivering such returned comminuted solids upstream relative to the preliminary coarse screen.

8. A combination sewage screening and comminuting apparatus comprising a flow-channel structure providing a screening chamber, an influent channel from which influent liquid is passed into an upstream section of said screening chamber and an effluent channel into which screened liquid is passed from a downstream section of said screening chamber, said channel structure embodying a bottom member providing in succession an upstream influent channel floor portion, a screening chamber floor portion and a downstream effluent channel floor portion of which said screening chamber floor portion is of low elevation as compared with the floor portions of the influent and effluent channels, said channel structure also embodying transversely-spaced side walls rising from said bottom and therewith forming a channel structure within and by which there is located and provided the aforementioned influent channel, as well as the screening chamber and the effluent channel, a tilttable bar screen located in said screening chamber of which the bars thereof are transversely spaced, transversely- and horizontally-extending axial line providing means carried by said channel structure and by which said screen is mounted so as to be tilttable about said axial line and at will placeable to either a normal operative or abnormal operative sewage screening position, and which screen when in either of said operative positions therefor functionally divides the screening chamber into an upstream influent receiving section and a downstream screened sewage section from which screened sewage passes into the effluent channel, which screen when tilted into its normal operative position divides the screening chamber whereby the influent receiving section inwardly extends below while the downstairs screened sewage section extends from above the screen, but which screen when tilted into its abnormal operative position divides the screening chamber whereby the influent receiving section inwardly extends above while the downstream screening section extends from below the screen; means for operatively positioning said tilttable screen about said axial line whereby at one time said screen is in its normal operative position with respect to said screening chamber whereat the under-face portion of the screen is the face initially engaged by the downstream flowing stream passing through the screen and whereby at another time said stream is in abnormal operative position whereat the previous upper-face portion of the screen is the face initially engaged by downstream flowing stream of the sewage passing through the screen, said screen being mounted positionably with respect to the flow-channel structure so that when in its normal operative position it provides

a screening roof over an underlying solids settling-out region within which the settled-out solids tend to collect, a disintegrating type of pumping means providing a suction conduit section with intake end leading from the aforementioned settling-out region, said pumping means also having a discharge conduit section available for returning pumped discharge to the sewage flow.

9. Apparatus according to claim 8, in which the pumping means has a discharge conduit section available for returning pumped discharge to the sewage flow at a locality upstream with respect to the tiltable screen.

10. Apparatus according to claim 8, in which there is a coarse screen interposed across the flow-channel structure at a locality upstream with respect to the influent receiving section of the screen chamber and in which the pumping means has a discharge conduit available for returning pumped discharge into the sewage flow at a locality upstream with respect to the coarse screen.

11. Apparatus according to claim 8, in which the pumping means has a discharge conduit section leading to and terminating directly over the screen when the latter is in normal operative position therefor and in which the pumping means has sufficient volumetric capacity to force liquid from said discharge conduit section downwardly through the screen against the flow of sewage normally upwardly through the screen.

12. A combination sewage screening and comminuting apparatus comprising a flow-channel structure embodying a bottom and transversely-spaced horizontally-extending walls rising therefrom and defining a downflow channel portion, a tiltable bar screen in said channel portion, a transversely- and horizontally-extending axial member mounted on said structure; means for operatively positioning said tiltable screen about the axis of said axial member for moving said screen with respect to said channel portion at one time into a normal operative stream-screening position at which the under face of the screen is initially engaged by the downflowing stream of sewage and at another time passing forwardly therethrough into an abnormal operative stream-screening position at which the previous upper surface portion of the screen is the face initially engaged by the downflowing stream of sewage passing therethrough, said screen being mounted on said axial member and positioned with respect to the flow-channel structure so that when in normal operative position it provides a screening roof overlying a solids settling-out region within which the settled-out solids tend to collect within the forward section thereof and through which the thus screened sewage flows forwardly and upwardly through said spaces between the bars of the screen and thence downstream with respect to the screen, a disintegrating type of pumping means having a suction conduit with intake end leading from a forward section of the aforementioned region overlain by the screen, which intake end is thusly located upstream with respect to the screen when in normal operative position therefor but is located downstream with respect to the screen when in its abnormal operative position, said pumping means having valve-controlled discharge conduit sections of which one when open is available for delivering pumped liquid downstream with respect to the screen when in normal operative position therefor and of which another when open is available for delivering pumped liquid against the downstream

5 side of the screen when the latter is in normal operative position therefor.

13. A combination sewage screening and comminuting apparatus according to claim 12, in which there is a screening grid upstream with respect to the tiltable screen and functioning as a screening means which is relatively coarse as compared with the tiltable screen and which said pumping means has a valve-controlled discharge conduit which when open delivers pumped liquid upstream with respect to the screening grid means.

14. A combination sewage screening and comminuting apparatus according to claim 12, in which the pumping means has three valve-controlled discharge sections of which one when open passes pump discharge to a locality upstream with respect to the tiltable screen regardless as to the position of the latter, of which another valve - controlled discharge section delivers pumped liquid into a region downstream with respect to the tiltable screen when in its normal operative position but upstream with respect to the tiltable screen when in its abnormal operative position, and a valve-controlled third section of which when the valve thereof is open delivers pumped liquid downstream with respect to said tiltable screen regardless of the operative position therefor.

15. A combination sewage screening and comminuting apparatus comprising a flow-channel structure embodying a bottom and transversely-spaced horizontally-extending walls rising therefrom and defining a downflow channel portion; a tiltable bar screen in said channel portion; a transversely- and horizontally-extending axial member mounted on said structure; means for operatively positioning said tiltable screen about the axis of said axial member for moving said screen with respect to said channel portion at one time into a normal operative stream-screening position at which the under face of the screen is initially engaged by the downflowing stream of sewage and at another time passing forwardly therethrough into an abnormal operative stream-screening position at which the previous upper face portion of the screen is the face initially engaged by the downflowing stream of sewage passing therethrough, said screen being mounted on said axial member and positioned with respect to the flow-channel structure so that when in normal operative position it provides a screening roof overlying a solids settling-out region within which the settled-out solids tend to collect within the forward section thereof and through which the thus screened sewage flows forwardly and upwardly through said spaces between the bars of the screen and thence downstream with respect to the screen; a disintegrating type of pumping means having a suction conduit with intake end leading from a forward section of the aforementioned region overlain by the screen, which intake end is thus located upstream with respect to the screen when in normal operative position therefor but is located downstream with respect to the screen when in its abnormal operative position, said pumping means having valve-controlled discharge conduit section which when open delivers pumped liquid downstream with respect to the screen when in normal operative screening position but upstream with respect to the screen when in abnormal operative screening position.
